(57) **CLAIM**

The ornamental design for a transparent dispensing lid, as shown and described herein.

DESCRIPTION

FIG. 1 is a perspective view of a transparent dispensing lid showing my new design in a closed position;

FIG. 2 is a rear elevation view thereof;

FIG. 3 is a top plan view thereof;

FIG. 4 is a front elevation view thereof; and,

FIG. 5 is a right elevation view thereof, which is a mirror image of a left elevation view thereof.
